BLADE OF PUMPS OR COMPRESSORS

Pierre Zens, Paris, France

Application January 18, 1934, Serial No. 707,197
In France January 30, 1933

3 Claimis. (Cl. 103—129)

This invention relates to improvements in the blades of pumps or compressors of the type in which systems of blades or pistons receive a variable movement, preferably in a cylinder, and particularly a gyratory or rotary movement about the longitudinal axis of the latter. The chambers, bounded by the blades and the cylinder owing to the relative angular displacements moving the blades of the various systems towards 10 and away from each other, have a variable volume so as to ensure the admission and delivery of the fluid through ports obturated and uncovered particularly by the rims of the blades.

The speed of this apparatus is actually limited 15 owing to the important alternate stresses exerted on the blades, thus frequently causing the latter to break in the region of the roots.

The present invention is adapted to remedy 20 this serious inconvenience and secure the attaining of high speeds of rotation.

The improvements forming the subject-matter 25 of the present invention, which more particularly relate to blades rigid with the corresponding hub on a portion only of their length, mainly consists in reinforcing the section of the root of 30 the blade in the region of the hub and in correspondingly diminishing the overhanging portion.

The portion of the blade corresponding to the 35 hub has a profile which is different from that of the overhanging portion, whilst preferably preserving the same width of rim, this difference being such that the corresponding faces of two adjacent blades of two systems can fit on each other notwithstanding the reinforcement of the hub and without increase of the total volume of 40 each blade.

The invention further relates to the following 45 points: (a) the longitudinal thrusts are absorbed by abutments situated on the respective shafts of these blades, so that these abutments are subjected only to the relative rotations of the blades. (b) the movable device thus constituted is held by a single member adjusting its position in the cylinder.

A reinforcement at the point of attachment of 50 the blades is thus obtained at the expense of the overhanging portion which serves only for covering the ports without modification of the rim and the distribution, and without creation of prejudicial space.

Owing to this reinforcement higher speeds of 55 rotation are permissible. The increase of the moment of inertia of the root enables hubs of small diameters to be used and the angle to be given to the blades then depends only on the speed of admission of the fluid through the ports, by virtue of which they may be given a minimum inertia. Moreover, the use of light alloys can 60 thus be resorted to, even for the root of the blades

and the hub, so that the hub and the blades can be made in one piece.

The invention also relates to a special arrangement of the inlet and exhaust ports, which consists in arranging the edges of these ports obliquely relatively to the corresponding edges 5 of the rims of the blades.

The invention has for further object other particular points which will appear from the following description with reference to the accompanying drawing, given by way of example 10 only and in which:

Fig. 1 is a perspective view of one of the three-blade units of a device comprising two movable units.

Fig. 2 is a perspective view of the other unit 15 combined with that illustrated in Fig. 1.

Fig. 3 is an elevation, in axial longitudinal section, of a compressor constructed according to 20 the invention.

Fig. 4 is a section, on a reduced scale, made according to line IV—IV of Fig. 3.

Fig. 5 is a section, on a reduced scale, made according to line V—V of Fig. 3.

Fig. 6 is a diagrammatic view of the form of 25 the pump blades at their point of closest approach.

The compressor illustrated by way of example only, comprises two units having relative angular displacements. The male unit is constituted as shown in Fig. 1; it comprises a shaft 1 and 30 three blades 2 rigid with this shaft on a portion only of their length. The female unit, illustrated in Fig. 2, is constituted by a tubular shaft 3 and by three blades 4 rigid with this shaft on a portion only of their length. These units are mounted, as indicated in Fig. 3, within a cylinder 5, the shaft 1 being fitted into the tubular shaft 3; means, of any suitable type, are provided for 35 rotatively driving, with a variable movement, the shafts 1 and 3, in order to cause, in the known manner, the volumes of the chambers 6 to vary.

Fig. 1 shows more particularly in perspective view the value of the reinforcement of the root. If the blade was traced, in the known manner, 45 for a blade angle AOB , the root would be ab . If, on either side of OA and OB , equal angles $aAN=aAM=bBP=bBQ$ are traced, it will be seen that the root thus obtained is QN greater than ab . On the contrary, the overhanging portion 50 has diminished according to a corresponding value.

If both these units are fitted into the cylinder 5, they can be given the same angular stroke as if 55 each blade had for profile the angle AOB , the rim, which covers the ports, being maintained.

Fig. 6 and the following explanations will allow 60 the principle of this feature of the invention to be more clearly understood.

The blades, whether they belong to either of

the two units, are subjected to equal stresses. If it is not desired to have a too large amount of metal on one of the units and to utilize under the best conditions the available spaces within the cylinder of the machine, it is necessary that all the blades should be similar from one unit to the other. The blades will therefore have equal widths at their periphery. Thus, in Figure 6, AB of the first unit is equal to BC of the second unit.

10 Whatever may be their shape, the blades must be symmetrical and, when their opposed faces touch each other from one unit to the other, if OX and OY are their axes of symmetry, one has

15 $XY = AB = BC$. According to the known methods, the radial plane OB is adopted as junction plane of the blades. In this case, the width of the blades at the root is $ab = bc$. This width depends on the 20 values of OB and of AB which, to a certain extent, are prescribed; ab or bc can be insufficient for resisting to the stresses under consideration. In order to remedy this inconvenience, the root of the blades AB might be reinforced, in its portion 25 connected to the hub, by wide fillets P, provided the portions of the blades BC are so shaped as to constitute overhanging portions, as illustrated, that is to say by cutting away their inner edges according to arcs of the circle P' superposable 30 on P.

35 The invention permits the reenforcement of the blades to the maximum extent at their point of attachment to the hub. It substantially consists in locating the contact planes of the opposite faces of the blades in the theoretical planes Ad, Bd, Be, Ce, the points d and e being the intersections of the axes OX and OY with the periphery of the hub.

40 Under these conditions, it will be seen that the width of the roots of the blades, at the hub, is df , that is to say twice the theoretical width $a-b$ of the known arrangements. The overhanging portions of the blades have for cross section the curvilinear triangles A d B.

45 This new profile causes the production of a longitudinal thrust of the gases against the blades. The stresses due to the pressure are exerted on the triangles AMN and BPQ and are counterbalanced but partially by the pressures acting on the ends 50 of the blades. These thrusts are absorbed by abutments situated between the concentric shafts rigid with each unit. The displacement of the abutments is limited to the relative displacement of one shaft relatively to the other. This abutment device, included in the scope of the invention, allows the adjustment of the laterally play 55 or clearance of the entire set of blades in the cylinder by means of a single member, preferably a double abutment combined with the extreme 60 bearing of the inner shaft.

65 The thrust of the gases or of the fluid tends to drive the blades 2, rigid with the inner shaft 1, in the direction $y-x$, and the blades 4, rigid with the outer shaft 3, in the direction xy . The interposition of roller or ball thrust bearings 10 between both shafts 1 and 3, annuls these translations and the adjustment of the position of the movable device in the cylinder 5 is effected by the adjustment of the double thrust bearing 11 situated 70 at the end of the inner shaft 1, this adjustment, in the example cited, being effected by means of a screw-thread provided in the cylinder head and by a stop screw 12. The blades 2

and 4, instead of being in one piece with the shafts 1 and 3, can be rigidly mounted on the latter, as illustrated, through the medium of the hubs 1^a and 3^a.

5 It will also be noted, according to the invention, that the inlet or exhaust ports 13 have edges which are oblique relatively to the edges of the rims of the blades in order to obtain silent working, by regularizing the displacements of the fluid.

10 The form of construction described and illustrated is given only by way of indication and not in a limiting sense. All modifications which do not alter in any way the main features above set forth and the desired result remain included in 15 the scope of the present invention.

What I claim as my invention and desire to secure by Letters Patent is:

1. In a pump or compressor having two systems of blades arranged in a cylinder to be subjected to relative angular displacements, each system comprising a hub with blades, carried by this hub and extending beyond the latter in overhanging position, an arrangement wherein the side faces of the blades in the portion attached to the hub 25 as well as in the overhanging portion are not in radial planes of the hub, the faces of the portions attached to the hub forming between them an angle less than the faces of the overhanging portions.

30 2. In a pump or compressor having two systems of blades arranged in a cylinder to be subjected to relative angular displacements, each system comprising a hub with blades carried by this hub and extending beyond the latter in overhanging 35 position, an arrangement wherein the side faces of the blades in the portion attached to the hub as well as in the overhanging portion, are not in radial planes of the hub, the faces of the portions attached to the hub forming between them an angle less than the faces of the overhanging portions, the angle between the peripheral face and the lateral face of the portion of the blade attached to the hub being in principle 40 the supplement of the corresponding angle of the 45 overhanging portion and all the blades being similar so that the opposed faces of two adjacent blades are adapted to fit against each other.

3. In a pump or compressor having two systems of blades arranged in a cylinder to be subjected to 50 relative angular displacements, each system comprising a hub with blades carried by this hub and extending beyond the latter in overhanging position, an arrangement wherein the side faces of the blades, in the portion attached to the hub 55 as well as in the overhanging portion, are not in radial planes passing through the axis of the hub, the faces of the portions attached to the hub forming between them an angle less than the faces of the overhanging portions, a double thrust 60 bearing interposed between the hub of one of the systems of blades and a shoulder on the shaft of the other system for absorbing the radial reactions of the compressed fluid on the blades, thrust bearings at one of the ends of the shaft 65 of one of the systems, means for longitudinally adjusting the said thrust bearing on the cylinder of the pump or compressor, the cylinder having ports inclined relatively to the peripheral edges 70 of the blades for constituting inlet and exhaust ports.

PIERRE ZENS.
